UNITED STATES PATENT OFFICE.

GORDON F. DODGE, OF NEW YORK, N. Y., ASSIGNEE TO ROBINS CONVEYING BELT COMPANY, OF PASSAIC, NEW JERSEY, A CORPORATION OF NEW JERSEY.

DRIVE MECHANISM FOR GRIZZLIES.

Application filed November 6, 1926. Serial No. 146,617.

The invention relates to mechanism primarily designed for driving the shafts of grizzlies for screening coke and similar material, which grizzlies comprise in their construction concurrently driven parallel shafts equipped with co-operating feeding and screening elements which present a succession of rows of separating openings for the material to be screened.

In grizzlies as generally heretofore constructed all the shafts have been coupled together by means of sprockets and chains in such a manner that when the center or drive shaft was actuated from a suitable source of power the motion was transmitted to the series of shafts. This, while a comparatively cheap type of drive, is not entirely satisfactory for various reasons. Amongst others, it is necessary to disconnect two driving chains in order to remove any shaft for repairs, or to disconnect all driving chains if all shafts are to be removed for the renewal of the material feeding and separating elements. Moreover, the power requirements through the various chains are cumulative from the end shafts toward the center or drive shaft.

An object of my invention is to provide a worm gear type of drive wherein there is no cumulative effect of power among the various shafts during the operation of the apparatus, and wherein each individual shaft drive may be made relatively lighter, yet ensuring longer service, than the chain type of drive referred to.

Another object of my invention is to provide a drive of such construction that the elements thereof can be readily removed for repair, and that the removal and renewal of the grizzly shafts and their appurtenances can be effected with facility.

Another object of my invention is to provide a drive wherein the gearing and bearings are continuously and effectually lubricated and protected from dust during the operation of the apparatus.

With these and other objects in view, my invention comprises novel features of construction and combinations of parts which will be hereinafter described and claimed.

In the drawings—

Figure 1 is a partial plan of a grizzly

equipped with driving mechanism embodying my invention, the pivotal casing at the upper end of the gear housing being in section.

Fig. 2 is a side elevation of the upper end of the gear housing and the casing.

Fig. 3 is a detail of the bearing for the jointed ends of the worm sections.

Fig. 4 is a partial side elevation of the grizzly showing the gear housing and casing in section.

Fig. 5 is a transverse section, as on the line 5—5 of Fig. 4.

Referring to the drawings, 10 designates one of the inclined side frames of a grizzly, which frame is provided with boxes 11 in which are journaled and beyond which extend the adjacent ends of a series of transverse shafts 12. These shafts are arranged in spaced parallel relation, and are equipped throughout the screening area with co-operating material feeding and screening elements, including disks 13. The projecting ends of the shafts are provided with my novel mechanism for concurrently driving the shafts in the same direction, which mechanism in its preferred construction is as follows:

Fast on the respective shafts 12 are worm wheels 14 which are adapted to mesh with a worm 15 extending longitudinally of the side frame. This worm, together with the wheels 14, is enclosed in a suitable dust and oil proof housing which is supported adjacent the side of the frame. The worm has its bearings in suitably-located boxes 16 within the housing, and the inner walls of the latter have appropriate stuffing boxes 17 through which the shafts 12 extend into the housing. The upper end of the housing terminates in a suitable casing 18 into which the proximate end of the worm shaft extends. This end of the worm shaft is equipped with a bevel gear 19 in mesh with a similar gear 20 on a power driven cross-shaft 21, which latter shaft has bearings in the respective sides or heads of the casing. Hence when the shaft 21 is driven from a suitable source of power the motion is transmitted from the shaft through the bevel gearing to the worm, and thence to the

series of gears 14 on the grizzly shafts when

such gears are in mesh with the worm, thus rotating the gears simultaneously and in the same direction, and this without any cumulative effect of power between the gearing of the succeeding grizzly shafts as obtains in the sprocket and chain mechanism heretofore employed. The only cumulative effect incident to the worm type of drive described is indicated by increasing end thrust and torsion on the worm, and, therefore, as a simple and efficient means to divide the end thrust between the worm shaft bearings, I make the worm in sections, preferably two as shown, and provide the meeting ends of the sections, within the adjacent bearing 16, with a longitudinal tongue and groove joint 22. This joint permits limited endwise motion of each section yet ensures the rotation of the two sections as a unit.

Where uniform speed of the succeeding shafts 12 is required counterpart worm wheels 14 on the respective shafts are employed, but if it be desired to increase progressively the speed of the shafts from the receiving to the discharging end of the apparatus, the succeeding worm wheels are provided with an equally reducing number of teeth and the worm is located in tangential relation to the pitch circles of the respective wheels.

The gear housing herein illustrated comprises upper and lower box sections, 23, 24, respectively, the lower section being bolted permanently in place to lugs 25 on the adjacent side frame of the grizzly, and the upper section being hingedly connected to the lower section. The upper section includes the bevel gear casing 18 and also supports the bearings 16 for the worm. The lower section has bolted thereto two side brackets 26 which embrace the heads of the casing. These brackets are provided with bearing members 26' which are fitted in central circular openings in the respective heads of the casing, thus constituting trunnions which enable the upper section of the housing to be readily swung up from or down upon the lower section, and also insure the proper alignment of the two sections (see Fig. 1).

The upper section is effectually locked in closed position upon the lower section by any suitable means so as to provide a dust and oil proof structure. In the present instance the lower section is provided at its respective ends with locking bolts 27 which are pivoted, as at 28, to suitably located corner lugs 29 on the lower section so as to be movable into and from complementary slotted lugs or keepers 30 on the upper section.

To open the housing it is merely required to slack off the nuts on the bolts 27 and swing the latter from the lugs 30, whereupon, by means, for example, of a suitable hoist attached thereto, the upper section can be

swung upward about its axial support on the brackets 26. The upper section is preferably provided at its lower end with a lifting eye 31 to which the hoisting means can be attached. By swinging the upper section of the housing a suitable distance above the lower section access can be readily had to the interior of the upper section for the purpose of removing any grizzly shaft, with its worm gear, bearings and material separating elements. The hinged or pivotal mounting of the upper section of the housing facilitates the operation of closing the housing and effecting the proper meshing of the worm and the series of worm gears, since in the lowering of the upper section the gears come into engagement consecutively with the worm and can be easily manipulated in respect to the opposing worm teeth. By removing the bolts that hold the brackets 26 to the lower section of the gear housing, the entire top of the housing and its appurtenances can be removed to facilitate repairs to the worm, worm bearings and associated parts.

In order to ensure the efficient lubrication of the worm gearing and bearings during the operation of the grizzly, the lower section of the housing is provided with transverse baffles 32 which are suitably-spaced apart to afford wells or compartments in which the respective worm gears 14 rotate. These compartments are kept supplied with oil into which each gear dips in its rotation, such gear thus being effectually lubricated and also carrying the oil upward to lubricate the rapidly rotating worm. A quantity of the oil thus delivered to the worm is thrown thereby against the roof of the housing and also against a cross-rib 33 which, overhanging each bearing, causes oil to drip into a suitably-disposed oil hole 34 in the top of the bearing. Oil is continuously circulated through the housing and the casing 18 by the agency of a circulating pump 35 which is conveniently supported on the upper section, adjacent the lower end of the latter. The inlet of this pump is connected by means of a pipe 36 with the lowermost compartment of the housing, and the outlet of the pump is connected to the casing 18 at the upper end of the housing by means of a pipe 37. Hence the oil is pumped from the lowermost compartment of the housing and delivered to the bevel gear drive contained in the casing, which oil is thus maintained in continuous circulation through the housing and casing during the operation of the pump.

It is to be understood that my invention is not limited to the particular construction herein disclosed, as the construction may be modified within the principle of my invention and the scope of the appended claims.

I claim—

1. In drive mechanism, the combination

with a plurality of parallel shafts, of worm gears thereon, a worm in mesh with said gears, a housing for said gears and worm, bearings in said housing for the worm, said worm comprising sections having capacity for limited longitudinal movement independently of each other, and means for actuating said worm, the meeting ends of said sections being rotatably supported in axial alignment by and within the adjacent bearing.

2. In drive mechanism, the combination with a plurality of parallel shafts, of worm gears thereon, a sectional worm in mesh with said gears, a housing for said gears and worm, bearings in said housing for the ends of the respective sections of the worm, said sections having at their meeting ends a tongue and groove joint which permits limited longitudinal movement of the respective sections, said meeting ends being rotatably supported in axial alignment by and within the adjacent bearing.

3. In drive mechanism, the combination with a plurality of parallel shafts, of worm gears at one end thereof, a worm in mesh with said gears, a housing for said gears and worm, said housing comprising a fixed section into which extend the ends of the shafts bearing the worm gears, and a complementary section movable to and from the fixed section, bearings in said complementary section for the worm, means for temporarily locking the complementary section in closing position, and means for actuating said worm.

4. In drive mechanism, the combination with a plurality of parallel shafts, of worm gears at one end thereof, a worm in mesh with said gears, a housing for said gears and worm, said housing comprising a fixed section into which extend the ends of the shafts bearing the worm gears, and a complementary section hingedly supported at one end of the fixed section and movable toward and from the latter, bearings in said hinged section for the worm, means for temporarily locking the hinged section in closed position, and means for actuating said worm.

5. In drive mechanism, the combination with a plurality of parallel shafts, of worm gears at one end thereof, a worm in mesh with said gears, a housing for said gears and worm, said housing comprising a fixed section into which extend the ends of the shaft bearing the worm gears, and a complementary section having an extended casing at one end, a hinge connection between said casing and the fixed section whereby the said complementary section can be bodily swung to and from the fixed section, bearings in said complementary section for the worm, a power shaft extending centrally into said

casing, and gearing between said shaft and the worm.

6. In drive mechanism, the combination with a plurality of parallel shafts, of worm gears at one end thereof, a worm in mesh with said gears, a housing for said gears and worm, said housing comprising a fixed lower section into which extend the ends of the shaft bearing the worm gears, and an upper section having an extended casing at one end thereof, side brackets arranged on the lower casing to embrace the heads of the casing, bearing members on said brackets fitted to circular openings in the respective heads and affording a hinge connection to permit the upper section to be swung up from or down upon the lower section, bearings in said upper section for the worm, a power shaft mounted in the said bearing members, and gearing between said latter shaft and the worm.

7. In drive mechanism, the combination with a plurality of parallel shafts, of worm gears thereon, a worm overlying said gears and in mesh therewith, a housing for said gears and worm, bearings for the worm in said housing, baffles within said housing providing oil wells in which the worm gears rotate, an oil pump, and oil circulating connections between said pump and different portions of the interior of the housing.

8. In drive mechanism, the combination with a plurality of parallel shafts, of worm gears thereon, a worm overlying said gears and in mesh therewith, an inclined housing for said gears and worm, bearings for the worm in said housing, baffles within said housing providing oil wells in which the worm gears rotate, each bearing having an oil inlet, cross-ribs on the roof of the housing overlying the bearings and their oil inlets, an oil pump, and oil circulating connections between said pump and the respective ends of the housing.

9. In drive mechanism, the combination with a plurality of parallel shafts, of worm gears thereon, a worm overlying said gears and in mesh therewith, an inclined housing for said gears and worm, said housing having an extended casing at one end thereof, bearings for the worm in said housing, baffles within said housing providing oil wells in which the worm gears rotate, gearing in said casing for continuously rotating the worm, an oil pump, and connections between said pump and the casing and between the pump and the opposite end of the housing.

Signed at New York in the county and State of New York this first day of November, A. D. 1926.
